UNITED STATES PATENT OFFICE.

WILLIAM HOLZER, OF HARRISON, NEW JERSEY.

MANUFACTURE OF INCANDESCING ELECTRIC LAMPS.

SPECIFICATION forming part of Letters Patent No. 293,879, dated February 19, 1884.

Application filed June 7, 1883. (No model.)

To all whom it may concern:

Be it known that I, WILLIAM HOLZER, of Harrison, in the county of Hudson and State of New Jersey, have invented a new and useful Improvement in the Manufacture of Incandescing Electric Lamps, of which the following is a specification.

In manufacturing the glass stem or wire support of an incandescing electric lamp the 10 leading-in wires are laid in a glass tube, and the end thereof is softened by heat and then pressed down upon the wires. It is necessary that this solidified portion of the glass should be cooled off gradually to anneal the 15 glass, as a sudden cooling would render the glass liable to fracture. My invention relates to a method and apparatus for accomplishing this gradual cooling of these parts. To this end I provide a series of stationary gas or 20 other burners, graduated to produce different temperatures decreasing from the first to the last of the series. The glass stem is inverted above these burners and passed over them one after another, lower degrees of heat being 25 thus successively applied and the glass being gradually cooled and annealed.

The preferable form of my invention is illustrated in the annexed drawings.

Figure 1 is an elevation of the cage which 30 incloses the apparatus; Fig. 2, an elevation, with a portion of the cage broken away; Fig. 3, a top view of the revolving portion which supports the glass stems, and Fig. 4 a top view of the gas-pipe and burners.

35 A is a suitable cage, having a sliding door, B, permitting access to its interior. Through the bottom of the cage passes a gas-pipe, *a*, to which is connected a circular pipe, *b*, supported from the bottom of the cage, and extending around the bottom, as shown. From 40 this pipe extend the series of gas-burners *c c*, of gradually-diminishing intensity. A stationary stem, *d*, rises from the center of the bottom of the cage and supports the sleeve *e*, which turns upon the stem. This sleeve supports by spokes *f* the rings *g g*, from each of 45 which project a number of pairs of spring-fingers, *h h*. The tubes *i*, having the wires sealed in them, are held by these spring-fingers, as shown.

When a tube is first placed in the apparatus, it is placed over the flame of greatest heat. After a time the sleeve and rings are revolved and the tube placed over the next flame, another tube being placed in position after the 55 first one. After a tube has passed over all the burners, remaining for a short time over each, and, finally, returning to the entrance, it is removed from the apparatus. A space is left without burners near the entrance to the 60 cage, so that the tubes can become entirely cooled by passing over this space before being removed. A spring-catch, *k*, carried by the stem *d*, is provided to stop the sleeve when the tubes are directly above the burners. In 65 practice, of course all the spring-fingers are kept constantly supplied with tubes, one being put in and started on the circuit as soon as one which has completed the circuit is removed.

I do not claim herein, broadly, the use of a series of stationary burners with lamp-holders traveling above them, whereby a gradual diminution of heat in the lamp is effected, since this is claimed in my application No. 97,337. 75

What I claim is—

1. The combination, with a ring of stationary burners of graduated relative intensity, of a circular frame revolving above the burners for supporting one or more incandescent lamp stems, substantially as set forth. 80

2. The circular gas-pipe, provided with a series of gas-burners, but with a portion of its length unprovided with burners, substantially as and for the purpose set forth. 85

3. The combination of the stationary series of burners, the stationary stem, the revolving frame provided with spring-fingers, and the stop for limiting the revolution of the frame, substantially as set forth. 90

4. The combination of the inclosing-cage, the stationary ring of burners, and the revolving frame for carrying the lamp-stems, substantially as set forth.

This specification signed and witnessed this 95 17th day of May, 1883.

WILLIAM HOLZER.
